UNITED STATES PATENT OFFICE.

HORACE E. SMYTHE, OF PITTSBURGH, PENNSYLVANIA, ASSIGNOR TO THE S. R. SMYTHE COMPANY, OF PITTSBURGH, PENNSYLVANIA, A CORPORATION OF WEST VIRGINIA.

FURNACE.

1,344,458.

Specification of Letters Patent. Patented June 22, 1920.

Application filed January 19, 1920. Serial No. 352,509.

To all whom it may concern:

Be it known that I, HORACE E. SMYTHE, a citizen of the United States, residing at Pittsburgh, in the county of Allegheny and

5 State of Pennsylvania, have invented new and useful Improvements in Furnaces, of which the following is a specification.

10 My invention relates to furnaces for heating ingots, slabs, billets, plates, or other metallic material and for annealing or heat treating the same. It is applicable also to open-hearth melting, copper smelting and other types of metallurgical furnaces.

15 The principal object of this invention is to assure proper combustion of the fuel constituents without regenerating the fuel gas. Each furnace is equipped with two reversing valves, one for gas and the other for air. The air-reversing valve is shifted 20 from time to time to cause the air for combustion to enter the furnace chamber alternately from opposite sides, and to cause the waste gases to pass therefrom through the reversing valve to the stack. The gas-reversing valve is also shifted to cause the 25 gas to enter the furnace chamber alternately from opposite sides along with the air, but the waste gases do not pass through this valve, which has no connection with the stack. By this arrangement there can 30 be no leaking of gas or fuel through the valve to the stack. No checkers are provided in the furnace for regenerating the gas, nor does any waste gas pass from the 35 furnace chamber through the gas passages, but all the waste gases pass through air regenerators which are connected to the stack by the air-reversing valve.

40 Referring to the accompanying drawings, which illustrate my invention in connection with a soaking-pit furnace for ingots, Figure 1 shows two furnaces separated by a division wall and employing a single stack flue, the lower half of the figure being a 45 plan view of one furnace and the upper half a horizontal section of the other furnace, the section being taken on the line I—I on Fig. 2. Fig. 2 is a vertical section of Fig. 1 on either line II—II; Fig. 3, a vertical section of Fig. 1 on the line III—III and also 50 on the line III^a—III^a, so far as it extends to the rear; and Fig. 4, a cross section on the line IV—IV on Fig. 1.

55 On the drawings, A and B designate two furnaces, having the same construction ex-

cept in a few details to which attention will be directed hereinafter. The upper half of Fig. 1 shows the furnace A and the lower half, the furnace B.

The furnaces have the common vertical 60 wall or partition 1 and the outer side walls 2 and 3. The rear portions of the furnaces have a less height than the central and forward portions, as they contain merely the stack flues, the reversing valves, and the 65 flues for carrying the gas and air to the said central and forward portions, and the waste products away from the latter. The central and forward portions, or what may be called the main portions, of the furnaces have 70 the front wall 4 and the rear wall 5, both reaching from the roofs 6 to the foundation, or floor 7.

75 The main portion of each furnace has a soaking-pit or furnace chamber 8 supported at some distance from the floor 7 by arches 9 and by the shoulders 10 in the thick transverse walls 11 and 12. Flues or combustion chambers 13 and 14 lie in each furnace between the roof 6 and the top of the respective transverse vertical walls or partitions 11 and 12 and preferably extend the entire width of each of these walls, that is, from the wall 1 to the outer wall of each furnace. The combustion chambers 13 and 14 in each 85 furnace are connected to the pit 8 by the passages 15 and 16, respectively, which are mere continuations of the combustion chambers. The combustion chambers 13 and 14 at their outer ends communicate by the 90 respective horizontal passages or ports 17 and 18 with the upper ends of the air regenerators or chambers 19 and 20, respectively. The ports 17 and 18 are openings through the vertical transverse walls or partitions 21 95 and 22, respectively, the latter being spaced from the vertical walls 11 and 12, respectively, so as to form the narrow vertical non-regenerative gas-supply chambers 23 and 24, respectively, which communicate 100 with the respective chambers 13 and 14 by means of the ports 25 and 26, respectively. The outer ends of the air chambers 19 and 20 are closed by the walls 4 and 5.

105 Each furnace has a pair of superposed gas-flues 27 and 28, the lower of which runs along the floor 7 and both of which lie in the furnace A along the wall 2, and in the furnace B along the wall 1. The flue 28 runs in each furnace from the rear end to the 110

- front end, where it opens into the bottom of the gas chamber 23, and the flue 27 runs forwardly only to the gas chamber 24, with the lower end of which it communicates. The 5 rear ends of the flues 27 and 28 open into the upwardly extending flues 29 and 30, respectively, which communicate with the opposite ends of the reversing-valve chamber 31, provided centrally above with the gas inlet 32. 10 Between this inlet and the flues 29 and 30 is the reversing valve 33 which, when in the full-line position, permits gas to enter the flue 29 and prevents it from entering the flue 30, and, when in the dotted position, permits 15 gas to enter the flue 30 and prevents it entering the flue 29.

Each furnace has also a pair of superposed air flues 34 and 35 parallel with the flues 27 and 28, and in the furnace A lying 20 next to the wall 1 and in the furnace B, next to the wall 3. Each flue 35 extends entirely to the front of its respective furnace and opens into the bottom of the respective regenerative chamber 19 while the flue 34 runs 25 only to the bottom of the regenerative chamber 20, into which it opens. The rear ends of the flues 34 and 35 open into the upwardly-extending flues 36 and 37 which open into the opposite ends of the valve casing 38, provided centrally above with the air-inlet 39. Between the inlet 39 and the flues 36 and 37 in each furnace is the reversing valve 40, which, when in the full-line position, permits air to enter the flue 36 and the 30 waste gases in the flue 37 to enter the flue 41 directly beneath the valve. From the flue 41 in each furnace the said waste gases traverse the rearwardly extending flue 42, which in each furnace opens into the 35 common stack flue 43. There is no flue connection between the reversing-valve casing 31 and the flues 41, 42, or 43.

The operation of one of the furnaces is as follows: The reversing valves 33 and 40 45 being in their full-line positions, the gas passes from the inlet 32 through the flues 29 and 27 into the gas chamber 24 and thence through the ports 26 into the combustion chamber 14, where it meets with regenerated 50 air coming from the inlet 39 by way of the flues 36 and 34, the regenerator chamber 20, and the ports 18. The burning gas passes 55 through the passage 16 into the soaking-pit, or furnace chamber 8, and thence to the stack flue 43 by way of the passage 15, the chamber 13, the ports 17, the regenerator chamber 19, the flues 35 and 37, the reversing valve casing, and the flues 41 and 42. In this operation the air is absorbing heat from the 60 previously heated regenerator chamber 20 and the waste products of combustion are heating the regenerator chamber 19. When the regenerator chamber 19 has become 65 properly heated, the reversing valves are shifted to the dotted-line positions, the gas

then passing from the inlet 32 through the flues 30 and 28, the chamber 23, and the ports 25 to the combustion chamber 13 where it meets air which flows from the inlet 39 through the flues 37 and 35, the regenerator 70 chamber 19, and the ports 17 to the combustion chamber 13. From the latter the burning gas passes through the passage 15 into the soaking-pit 8, from which the waste gases pass to the stack flue 43 by way of 75 the passage 16, the chamber 14, the ports 18, the regenerator chamber 20, the flues 34 and 36, the valve casing 38, and the flues 41 and 42. In this case the regenerator chamber 80 20 is reheated while the air is absorbing heat from the chamber 19. The complete operation just given is repeated as long as the furnace is in operation.

It is to be noted that the waste gases do not reach the stack by way of the gas-reversing valve, but wholly through the air-reversing valve. There is, therefore, no leakage of gas from the gas-reversing valve casing to the stack as would occur if the waste products should traverse the same. 85 The heated air from the air regenerators 19 and 20 passes through ports in the walls dividing them from the gas chambers 23 and 24 and then passes directly over the top of the gaseous fuel coming from the ports 25 and 26, thereby effecting a proper, economical, and improved combustion. All the waste gases pass through air regenerators only, thereby preheating the air to a high 90 temperature and assuring proper combustion. 100

In case this invention is to use natural gas or fuel oil introduced through pipes, the pipes would deliver the fuel alternately to the ports 25 and 26, while the air would pass 105 as described. Coke oven gas and blast furnace gas would be introduced in the same way.

I claim:

1. In a furnace structure, a furnace chamber, means for reversing the flow of air and gas to the said chamber, a stack flue, and means preventing the waste gases from flowing through the gas reversing means and through the gas passages between the chamber and the gas reversing means. 110

2. In a furnace structure, a furnace chamber, a combustion chamber opening into each side of the furnace chamber, a gas-reversing means, a passage leading from the said means to each combustion chamber, an air regenerator connected to each combustion chamber, an air-reversing means, a passage leading from the last named means to each regenerator, and a stack flue connected to the 120 air-reversing means only. 125

Signed at Pittsburgh, Pa., this 10th day of January, 1920.

HORACE E. SMYTHE.
